Patented Dec. 28, 1920.

INVENTOR:
Herman H. Quehl
Walter F. Murray
Atty.

UNITED STATES PATENT OFFICE.

HERMAN H. QUEHL, OF CINCINNATI, OHIO, ASSIGNOR TO WHITE-QUEHL MANUFACTURING COMPANY, OF CINCINNATI, OHIO, A FIRM.

LAUNDRY-TAG.

1,363,349.

Specification of Letters Patent.

Patented Dec. 28, 1920.

Application filed March 28, 1919. Serial No. 285,870.

To all whom it may concern:

Be it known that I, HERMAN H. QUEHL, a citizen of the United States of America, and a resident of Cincinnati, in the county 5 of Hamilton and State of Ohio, have invented a new and useful Improvement in Laundry-Tags, of which the following is a specification.

An object of my invention is to produce 10 an improved laundry tag in which the tag material is held in position and condition to receive the written or printed matter thereon, previous to the affixing of the tag, with no metal portion to interfere with the 15 marking of the tag or the laundering of an article to which it is attached.

This and other objects are attained in a laundry tag described in the following specification, and illustrated in the accompanying 20 drawings, in which:—

Figure 1, is a perspective view of a laundry tag embodying my invention, a portion thereof being broken away for clearness of illustration.

25 Fig. 2, is a transverse sectional view of my improved tag, taken on the line 2—2 of Fig. 1.

Fig. 3, is a transverse sectional view of the material upon which the identification 30 marks are placed, taken upon the line 3—3 of Fig. 1, and showing only the material.

Fig. 4, is a perspective view of one of the tag staples used to affix the tag embodying 35 my invention to an article to which it is to be attached.

Fig. 5, is a transverse sectional view of a modified form of tag embodying my invention.

Fig. 6, is a transverse sectional view showing 40 a modified form of the material upon which the identification marks are placed, and which is used in the form of tag disclosed in Fig. 5.

My improved tag consists of a mark receiving material 7, and staples 8 and 9 which are preferably located at the ends of the material and which are used for securing the tag in position upon an article to which it is to be attached.

50 The mark receiving material consists of a tape of fabric having its longitudinal edges turned in to substantially engage each other as disclosed at 10 and 11, thus forming a somewhat tubular member. The upper or

writing surface portion 12 of the member 7 55 is left free from end to end for receiving the identification marks, by passing the middle portion 13 of each of the staples through the sides of the tag and between portion 12 and edges 10 and 11. Inturned clamping 60 portions 14 and 15, are formed on the staples for clamping mark receiving material in position against displacement as shown in Fig. 1. The pointed ends 16 and 17 of the staple are then bent down at right angles to the 65 remaining portions so as to be in position to be passed through the article to which the tag is to be secured. After having been passed through the material the ends 16 and 17 are pressed into overlapping side by side 70 positions with relation to each other, thus securely fastening the tag against displacement from the material.

In the modified form of my invention disclosed in Figs. 5 and 6, the mark receiving 75 member 7^a is provided with overlapping edges 10^a and 11^a, instead of edges which meet one another as disclosed in Fig. 1. The fastening staples are identical with the fastening staples disclosed in the first described 80 form of my invention. The modified form of my invention results in a more durable construction because of the increased strength afforded by the overlapped edges 10^a and 11^a. 85

Having thus described my invention what I claim is:—

1. A laundry tag comprising a mark receiving member, and a staple adapted to secure the member in position upon an article 90 to be laundered, the member consisting of a strip of material having the edges turned in toward one another to form a substantially flat tubular member having a mark receiving space, the staple having a central 95 portion located between the mark receiving space and the inturned edges, a portion inturned at each end of the central portion and adapted to clamp the inturned portions of the mark receiving member between the 100 central portion and the last mentioned staple portion, and prongs extending from the last mentioned portions, adapted to be passed through the material to be laundered and to be moved into clamping engagement 105 therewith.

2. A laundry tag comprising a mark receiving member, and a staple adapted to se-

cure the member in position upon an article to be laundried, the member consisting of a strip of material having the edges turned in to engage each other and form a substantially flat tubular member having a mark receiving space, the staple having a central portion passing transversely of the tag and located between the inturned edges and the mark receiving space, the inturned

portions at the ends of the central portion 10 adapted to clamp the inturned edges of the member, and prongs extending from the staple adapted to secure the staple to the article to be laundried.

In testimony whereof I have hereunto 15 subscribed my name this 26th day of March, 1919.

HERMAN H. QUEHL.
